(57) **CLAIM**

The ornamental design for a paper roll dispenser, substantially as shown and described.

DESCRIPTION

FIG. 1 is a top, front and right side perspective view of a paper roll dispenser showing our new design;

FIG. 2 is a front elevational view thereof;

FIG. 3 is a left side view elevational thereof, the right side being the mirror image thereof;

FIG. 4 is a rear elevational view thereof;

FIG. 5 is a top plan view thereof; and,

FIG. 6 is a bottom plan view thereof.

The broken-line disclosure of the paper rolls in the views is for illustrative purposes only and forms not part of the claimed design.
